UNITED STATES PATENT OFFICE.

GUSTAV HILGENBERG, OF HANOVER-BADENSTEDT, GERMANY.

DRIER.

Application filed June 17, 1926, Serial No. 116,712, and in Germany December 29, 1924.

This invention has reference to substantially drum-shaped rotary drying devices and it is particularly adapted for the drying of granular material, such as salt from salterns or salt-works, crystal-sugar, alum and the like, and among other important advantages it provides means of substantially avoiding the destruction or injuring of the configuration and outer appearance of the material, and the overheating and discoloration thereof. Material of the kind referred to and similar goods are to be dried slowly, and at comparatively low temperature and with as little mechanical handling as possible, so as to retain the purity and the nice crystallized shape of the material. With this end in view so-called plate driers have been disclosed in the previous art in which the material is distributed on coaxially and spacedly superimposed annular surfaces, the so-called plates or dishes, arranged to revolve on a vertical shaft and cooperating with relatively stationary scrapers or wipers adapted to cause the material to travel continuously from the top to the bottom plate and through the entire system of plates or dishes. Such coaxially disposed annular surfaces are ordinarily arranged, so as to retain a certain radial distance from the axis of the device, inasmuch as the rotary speed of the plates or dishes should be comparatively low, while their longitudinal extension should be comparatively large. If in such devices the surfaces of the plates would be made to reach up to the shaft, the revolving speed adjacent the shaft would be much too low, and it would be impossible to arrive at a sufficiently long travelling passage for the drying of the material at those points situated adjacent the rotary shaft of the device. In view thereof it was customary to arrange a free vertical cylindrical space between the drying section proper containing the revolving drying surfaces and the shaft, this space containing merely the connecting means between the shaft and the circulating or revolving plate surfaces, but being otherwise not utilized.

Now, my invention is distinguished by the fact that the central cylindrical shaft space is made to constitute a closed heating channel which is connected at its bottom to the admission means for the heating agent, while at its top it is connected to the educting passage.

The invention will be more particularly

described with reference to the accompanying drawing showing by way of exemplification a form of embodiment of the principles of the invention in Figure 1 in vertical longitudinal section, and in Figure 2 in horizontal section. Figure 3 is a modified construction shown in vertical longitudinal section. In the drawing:—*f* are the otherwise well-known substantially annular plates or dishes, adapted for slow rotary movement on the vertical central axis; they are spacedly superimposed and may be staggeringly arranged. They are disposed in an annular or cylindrical casing, as appears from the drawing. In the exemplification illustrated the outer wall of the casing is immovable, and the interior wall of the casing is connected by suitable struts, stays or the like to the shaft, and upon the outer surface of the interior wall of the casing the plates or dishes *f* are disposed. *d* are tightening means, sealing means or the like of any well-known or other construction at those places where the relatively stationary wall of the casing is connected to the rotatable wall thereof.

The heating agent is introduced from below and from a stationary channel *a* into the central tubular space *b*, and it is laterally conducted away from the top of the central space by means of a channel *c* adjacent the outer surface of the drying room through which the heating gases are made to descend.

The direct heating of the drying material itself may be effected in the usual manner by causing hot air to flow through the annular casing either in the equal current or in the counter-current direction as indicated in Figure 3 of the drawing in which the full-lined arrows *H* show the course of the drying fluid in the counter-current direction with relation to the descending material under treatment, while the broken-line arrows *G* indicate both the downward movement of such material as well as the alternative flowing of the drying fluid in the equal direction. The openings *n* and *n'* provided in the annular casing serve for the charging and the escape of the material, and may also be utilized for the purpose of causing heating fluid to flow through the said annular space.

The material to be dried is introduced from the top into the casing, and it is removed from the bottom of the casing. The material may be pushed forward along the

individual plates and from one plate to the other by means of wipers or scrapers *g* indicated in the drawing and of any suitable size and construction. The relative arrangement, 3 position and shape of the dishes or plates *f* is immaterial and may be of any desired kind, being mainly governed by the particular kind and condition of the material under treatment.

10 In the preferred construction the heating agent passes from the flue or channel *a* upwards into the central shaft space *b*. Inasmuch as this space is of relatively large cross section, the heating gases are caused 15 to slowly ascend therein, so as to efficiently transmit their heat to the interior casing wall which carries the plates *f* and is rotated with them. By this means the heat is retained and condensed in the center of the device and is only allowed to spread on all 20 sides in the radial direction, and a very superior utilization of the heat is thereby obtained as compared with other suggestions employing exterior heating. In view of the 25 fact that plate driers of this general type are usually constructed of large dimensions the heating of the device by means of a central shaft constitutes moreover a very important saving of material, and in this arrangement the heating gases after leaving the central heating space may be caused to 30 flow along the outer surface, bathing the same and thereby increasing the direct heating surface by suitably shaping and arranging the channel *c*, without thereby in any way interfering with the easy accessibility from without of the drying room.

35 The rotary interior shell of the casing encompassing the heating flue *b* may be made of corrugated sheet metal with the corrugations horizontally directed as shown at *T* in Figure 3 of the drawing whereby the advantage is obtained that the heating surface is increased, while the rigidity of the shell and of the entire casing is also augmented. Furthermore, the central heating space *b* may 40 contain guiding or abutting means of any suitable construction and arrangement and indicated diagrammatically at *W* in Figure 45 3 of the drawing, such for instance as alternately or staggeringly arranged horizontal walls, partitions or sheet metal plates or the like, so as to suitably increase the 50 path of the heating gases.

55 The fuel employed for heating purposes may be of any desired kind. Heating gases or heated air from any suitable source of heat may be caused to flow through the centrally disposed heating space *b*, or special 60 heating bodies may be provided in this central channel or in the channel *a*, as shown at *K* in Figure 3 of the drawing. It is evident that various other means may be employed for the purpose of introducing the 65 heating fluid into the space *b*.

The outer surfaces of the drying device may be protected against radiation of heat by suitable heat insulating and protecting means shown at *S* as a coating of felt, asbestos or the like in Figure 3 of the drawing, and the metal and other parts may be covered with a heat-resisting coating of paint.

An additional current of air or the like 70 may be led through the drying space, so as to carry away the vapors and to assist in the drying operation, such air current or the like being passed through the openings *n*, *n'*, Figure 3, in the same manner as above outlined with reference to the circulation of heating fluid through such space.

By means of the construction according to this invention a very thorough utilization of heat and a very uniform distribution of the heat and of the material with a very important saving of constructional material may be realized, so that important advantages will result from the new methods of drying according to this invention in which all the parts of the material are subject to a certain translatory motion of their own combined with a high degree of heating efficiency.

While I have described my invention by way of illustration with reference to a certain manner of embodiment, I am not restricted thereto, and may employ different changes and modifications in connection therewith; thus I may cause the heating gases to enter the device in the downward direction or I may make other changes in the arrangement and construction and operation of parts without deviating from the spirit and scope of the invention, except as hereinafter specified and stated in the appended claims.

I claim:—

1. In a drying device in combination a cylindrical interior heating chamber and an outer cylindrical casing, spacedly surrounding the interior chamber and rotatable with relation to each other, and supporting means for the material under treatment, spacedly superimposed in the annular space between the inner and outer casing and spacedly secured to the rotatable casing for rotation therewith intermediate the inner and outer casings.

2. In a drying device in combination, a cylindrical interior heating casing and an outer cylindrical casing, spacedly surrounding the same and rotatable with relation to each other, supporting means for the material to be treated, spacedly superimposed in the annular space between the casings and secured to the inner casing, and an educting channel for the heating gases adjacent the outer casing and communicating with the interior casing.

3. In a drying device in combination, a cylindrical interior heating casing and an

- outer, substantially concentric cylindrical casing, spacedly surrounding the same, said casings being rotatable with relation to each other, supporting means for the material under treatment and staggeringly and spacedly superimposed in the annular space between the casings and secured to one of said casings, and wiping means cooperating with the supporting means.
4. In a drying device in combination, a cylindrical interior heating casing and an outer, substantially concentric cylindrical casing, spacedly surrounding the same, heat admitting means at the lower end of the interior casing, and heat educting means at the outside of the outer casing and substantially adjacent the same and communicating with the top of the inner casing.
5. In a drying device in combination, a cylindrical, substantially horizontally corrugated interior heating casing, and an outer cylindrical casing spacedly surrounding the same and rotatable with relation to each other, and supporting means for the material under treatment, spacedly superimposed in the annular space between the casings and spacedly secured to the interior walls of said space.
6. In a drying device in combination, a cylindrical interior heating casing, an outer cylindrical casing, spacedly and concentrically surrounding the same and rotatable with relation to each other, and supporting means for the material in the annular space between the casings and superimposedly fastened to the interior walls of said space.

GUSTAV HILGENBERG.
